United States Patent Office

Des. 221,150
Patented July 13, 1971

221,150

DENTAL CABINET OR THE LIKE

Kenneth R. Ferguson, Jr., Charlotte, N.C., assignor to
Pelton & Crane Company, Charlotte, N.C.

Filed June 12, 1970, Ser. No. 23,448

Term of patent 14 years

Int. Cl. D24—03; D6—01

U.S. Cl. D24—1

The figure is a front perspective view of the dental cabinet showing my new design.

The back and sides of the dental cabinet (not shown) are substantially plain and unornamented.

I claim:

The ornamental design for a dental cabinet or the like, substantially as shown and described.
